11 Claims. (Cl. 62—197)

This invention relates to heat pumps, and more particularly to improved means for increasing the efficiency of heat pumps.

Heretofore, heat pumps have never been widely accepted because of their low efficiency and costly operation, especially in the northern climates. With the subsequent development of more efficient compressors, the heat pump found some application in the warmer climates, but still proved undesirable in the northern climates because of low efficiency and high operational costs.

The present invention overcomes the above problems by reducing the amount of work to be done per unit of refrigeration or per unit of heating accomplished. Thus, the efficiency of the heat pump has been greatly increased by the present invention. This is made possible by intercooling the refrigerant in the compressor while it is being compressed in an effort to follow the vapor saturation line by injecting a predetermined amount of refrigerant directly into the compressor starting at the beginning of the compression and ending before the end of compression.

Accordingly, it is an object of this invention to provide an improved heat pump having an efficiency greater than any heat pump heretofore developed.

Another object of this invention resides in the provision of a heat pump having means for reducing the amount of work to be done per unit of refrigeration or per unit of heating accomplished.

Still another object of this invention is in the provision of a heat pump having means for intercooling the refrigerant in the compressor while it is being compressed.

A further object of this invention is to provide a heat pump having means for injecting a predetermined amount of refrigerant directly into the compressor starting at the beginning of the compression and ending a little before the end of compression.

A still further object of this invention is to provide a heat pump having a refrigerant charging unit for injecting a predetermined amount of liquid refrigerant into the compressor during the compression stroke and in response to the compression stroke.

A still further object of this invention is in the provision of a heat pump having a refrigerant injection unit operable in response to the compressor for injecting a measured charge of liquid refrigerant under high pressure into the compressor, whereby the injection unit may be adjusted to vary the amount of charge injected into the compressor.

Other objects, features, and advantages of the invention will be apparent from the following detailed disclosure, taken in conjunction with the accompanying sheet of drawings, wherein like reference numerals refer to like parts, in which:

Fig. 1 is a diagrammatic view of a heat pump according to the invention and illustrating a vertical sectional view of the refrigerant injection unit with the parts positioned prior to the initiation of the compression stroke in the compressor;

Fig. 2 is a fragmentary view of the heat pump, illustrating the positions of the parts during the compression stroke, when a measured charge of refrigerant is injected into the compressor; and

5 Fig. 3 is a pressure-enthalpy diagram illustrating the thermodynamic processes involved when comparing the straight compression process heretofore known and the intercooling process of the present invention.

Referring now to the drawings, and particularly to Fig. 10 1, the heat pump of the present invention includes generally a compressor 10, a condenser 11, and an expansion or throttling valve 12, an evaporator 13, and a refrigerant injection unit 14.

The compressor 10 is of the reciprocating type and 15 includes a piston 15 reciprocable in a cylinder 16 and defining a compression chamber 17. It may be appreciated that other types of compressors may be employed, although the present invention will be hereinafter described in connection with a reciprocating compressor.

20 Low pressure gas refrigerant is conveyed from the evaporator to the compressor by a line or conduit 18. This low pressure gas refrigerant is then compressed by the compressor and conveyed through the line 19 to the condenser 11. The high pressure gas refrigerant is condensed by the condenser thereby giving off heat and lowering its temperature. The high pressure liquid refrigerant is then conveyed to the evaporator 13 through a line or conduit 20. As the high pressure liquid refrigerant passes through the expansion or throttle valve 25 30 12, its pressure is reduced prior to entering the evaporator. The liquid refrigerant is then evaporated in the evaporator by adsorption of heat and low pressure gas is returned to the compressor through the line 18.

The refrigerant injection unit 14 includes a casing 21 35 having large and small connected stepped bores 22 and 23 slidably receiving therein a floating piston 24 having large and small stepped portions 25 and 26. The casing is closed at one end by an end wall 27 and at the other end by an end wall 28. The free end of the piston portion 25 defines with the end wall 27 a working chamber 30 35 intercommunicating directly with the compression chamber 17 of the compressor 10 by a line or conduit 30.

Upper and lower annular shoulders having resilient rings 31 and 32 of neoprene, rubber, plastic or equivalent 40 suitable material are provided within the larger bore 22 for determining the limits of movement of the piston 24 and for cushioning movement of the plunger to reduce shock and noise. Additionally, an adjustable stop 33 is threadedly received in the end wall 27 and adapted to engage 50 the lower end of the piston 24 to further limit the movement of the piston adjustably to vary the measured charge to be injected into the compressor as will be hereinafter more clearly explained. A resilient pad 33a of neoprene, rubber, plastic or equivalent suitable material is secured 55 to the piston engaging end of the stop 33 to cushion the return stroke of the piston. A venting chamber 34 is defined above the larger piston portion 25 and intercommunicated with the low pressure return line 18 by a line or conduit 35.

60 At the upper end of the casing, a necked or restrictive portion 36 is spaced inwardly from the end wall 28 and defines a seat for a check valve member 37 resiliently biased thereagainst by a spring 38 and defining a check valve. The check valve defines with the free end of the 65 piston portion 26 a charge chamber 39 intercommunicated with a source of high pressure liquid refrigerant by means of a line or conduit 40 extending to the line 20 ahead of the expansion valve 12. A one-way or check valve 41 is arranged in line 40 to permit flow of refrigerant to the charge chamber 39, but prevent backflow through the line 40.

The discharge side of the check valve 37 is intercom-

municated with the compression chamber 17 of the compressor by means of a line or conduit 42 and this check valve only permits flow toward the compressor.

Springs 43 and 44 are received in the casing and act on opposite sides of the larger piston portion 25 to aid in maintaining the piston floating in the casing. The spring 44 is slightly stronger than the spring 43 and serves to return the piston to normal position after it has injected a measured charge of refrigerant into the compressor.

It will be appreciated that the refrigerant injection unit of the present invention which provides the intercooling process may be employed with single or multi-stage compressors, although shown and described herein with a single stage unit.

Operation of the heat pump and the refrigerant injection unit of the present invention is initiated at the beginning of the compression stroke of the compressor 10, when the piston 15 begins its upward movement to compress the low pressure gas in the compression chamber 17. It will be appreciated that the charge chamber 39 is already filled with high pressure liquid refrigerant delivered through the line 40 from the discharge side of the condenser. As the low pressure gas is compressed in the

jection unit and the quality of this diverted refrigerant as follows:

A. Quality of refrigerant at point H_3 =

$$5 \quad x = \frac{H_3 - H_6}{H_4 - H_6} = \frac{31.16 - 17.00}{82.71 - 17.00} = .215$$

B. Work necessary for the intercooling process=

$$H_1 - H_5 = 90.85 - 88.62 = 2.23 \text{ B.t.u./lb.}$$

10 C. Weight of refrigerant necessary to cool 2.23 B.t.u./lb.=

$$15 \quad \frac{H_1 - H_5}{(1-x)(H_4 - H_6)} = \frac{2.23}{(1-.215)(82.71 - 17.00)} = .0432 \text{ lb./lb. of refrigerant}$$

D. Weight of refrigerant passing through evaporator=

$$W = 1 - 0.0432 = .9568 \text{ lbs.}$$

20

Now the refrigeration and coefficient of performance of the thermodynamic process according to the present invention may be calculated as follows:

$$= H_5 - H_4 = 88.62 - 82.71 = 5.91 \text{ B.t.u./lb.}$$

$$= (H_4 - H_2)W = (82.71 - 31.16)0.9568 = 49.40 \text{ B.t.u./lb.}$$

$$3. \text{ Coefficient of performance} = \frac{\text{refrigeration}}{\text{work}} = \frac{49.40}{5.91} = 8.34 \text{ B.t.u./lb.}$$

compression chamber 17, this pressure is reflected in the working chamber 29 to act on the lower end of the piston 24, forcing it upwardly to discharge the refrigerant charge in the charging chamber 29 therefrom by unseating the check valve 37, as seen in Fig. 2, and forcing the charge of liquid refrigerant into the compressor in the form of finely atomized droplets which evaporate in the lower pressure environment. This evaporation cools the compressed gas refrigerant with an overall gain in efficiency and reduction of work involved in the cycle.

In order to more clearly understand the present invention, the thermodynamic process will be compared with that of a straight compression cycle.

An example of a one-stage compression, as seen in Fig. 3, with conditions as 40° F. evaporator and 100° F. condenser using Freon-12 as refrigerant is as follows:

$$1. \text{ Work} = H_1 - H_4 = 90.85 - 82.71 = 8.14 \text{ B.t.u./lb.}$$

$$2. \text{ Refrigeration} = H_4 - H_2 = 82.71 - 31.16 = 51.55 \text{ B.t.u./lb.}$$

$$3. \text{ Coefficient of performance} = \frac{\text{refrigeration}}{\text{work}} = \frac{51.55}{8.14} = 6.35$$

As seen on the pressure-enthalpy diagram in Fig. 3, this process of compression is from point H_4 to point H_1 . Ordinarily this is an isentropic process which requires a certain amount of work to be carried out. For this particular case as set forth above in the example, 8.14 B.t.u. of work per pound of refrigerant is required.

The amount of work is reduced according to the present invention for the same amount of refrigeration by cooling the compression process as it takes place thereby obtaining a final point H_5 instead of point H_1 , on the pressure-enthalpy diagram which closely follows the vapor saturation line or curve 45. Even though it is necessary to use a portion of the refrigerant for the intercooling process and divert it from the evaporator, the net efficiency is increased.

Before calculating the refrigeration accomplished by the present invention, it is first necessary to determine the amount of refrigerant diverted to the refrigerant in-

Accordingly, the amount of work necessary to accomplish the same amount of refrigeration with the intercooling compression process of the present invention is 5.91 B.t.u. of work per pound of refrigerant. This is considerably less than 8.14 B.t.u./lb., that is required in the straight compression process.

Assuming the compressor efficiency is 80% and the refrigerant injection unit efficiency is 80%, the net efficiency increase may be calculated as follows:

$$1. \text{ No intercooling} \quad 6.35 \times .80 = 5.08$$

$$2. \text{ With intercooling} \quad 8.34 \times .80 = 6.67$$

$$45 \quad \text{Increase in efficiency} = \frac{6.67}{5.08} = 1.31 \text{ or } 31\%$$

$$\text{Net increase in efficiency} = .31 \times .80 = 24.8\%$$

In view of the foregoing, it may be appreciated that 60 the present invention provides a heat pump having a refrigerant injection unit providing an intercooling process which considerably increases its efficiency thereby making it more desirable for commercial usage.

It will be understood that modifications and variations 65 may be effected without departing from the scope of the novel concepts of the present invention, but it is understood that this application is to be limited only by the scope of the appended claims.

The invention is hereby claimed as follows:

70 1. In a heat pump including a compressor, an evaporator, a condenser, an expansion valve, a low pressure line between the compressor and evaporator, a first high pressure line between the compressor and condenser, and a second high pressure line between the condenser and evaporator having the expansion valve therein, the improvement of means connected between the second high

pressure line and the compressor receiving liquid refrigerant and being responsive to the compressing action of the compressor to increase the pressure of the liquid refrigerant and inject a predetermined amount of liquid refrigerant of increased pressure into the compressor.

2. In a heat pump including a reciprocating compressor, an evaporator, a condenser, an expansion valve, a low pressure line between the compressor and evaporator, a first high pressure line between the compressor and condenser, and a second high pressure line between the condenser and evaporator having the expansion valve therein, the improvement of means connected between the second high pressure line on the inlet side of said expansion valve and the compressor receiving high pressure liquid refrigerant and being responsive to the compression stroke of the compressor to increase the pressure of the liquid refrigerant and inject a charge of the liquid refrigerant of increased pressure into the compressor.

3. In a heat pump including a compressor, an evaporator, a condenser, an expansion valve, a low pressure line between the compressor and evaporator, a first high pressure line between the compressor and condenser, and a second high pressure line between the condenser and evaporator having the expansion valve therein, the improvement of means connected between the second high pressure line on the inlet side of said expansion valve and the compressor receiving high pressure liquid refrigerant and being responsive to the compressing action of the compressor to increase the pressure of the liquid refrigerant and inject a charge of the liquid refrigerant of increased pressure into the compressor, and means on said first means for adjusting the quantity of said charge.

4. In a heat pump including a compressor having a compression chamber, an evaporator, a condenser, an expansion valve, a low pressure line between the compressor and evaporator, a first high pressure line between the compressor and condenser, and a second high pressure line between the condenser and evaporator having the expansion valve therein, the improvement of means connected between the second high pressure line and the compression chamber of the compressor being responsive to the compressor to inject a predetermined amount of liquid refrigerant into the compressor, said means comprising a casing having a charge chamber therein, said second high pressure line connected to said chamber, a one-way valve between said chamber and said condenser, a line interconnecting the chamber to said compressor, a second one-way valve between said chamber and said compressor, and a piston in said casing responsive to the compressing action of said compressor for forcing the charge in said chamber into said compressor.

5. In a heat pump including a reciprocating compressor having a compression chamber, an evaporator, a condenser, an expansion valve, a low pressure line between the compressor and evaporator, a first high pressure line between the compressor and condenser, and a second high pressure line between the condenser and evaporator having the expansion valve therein, the improvement of means connected between the second high pressure line and the compression chamber of the compressor being responsive to the compressor to inject a predetermined amount of liquid refrigerant into the compressor, said means comprising a casing having a charge chamber therein, said second high pressure line connected to said chamber, a one-way valve between said chamber and said condenser, a line interconnecting the chamber to said compressor, a second one-way valve between said chamber and said compressor, and a floating piston in said casing responsive to said compression stroke of the compressor for forcing the charge in said chamber into said compressor.

6. A heat pump comprising a reciprocating compressor, an evaporator, a condenser, a pressure actuated refrigerant injection unit, and a refrigerant circulating in said pump, a first high pressure line connecting the com-

pressor and condenser, a low pressure line connecting the evaporator and compressor, a second high pressure line connecting the condenser and evaporator, an expansion valve in said second high pressure line, and a high pressure line connecting said second high pressure line and said injection unit, said injection unit being responsive to the compression stroke of said compressor to increase the pressure of refrigerant received thereby and inject a charge of said refrigerant of increased pressure into the compressor.

7. A heat pump comprising a compressor having a compression chamber, an evaporator, a condenser, a refrigerant, a line connecting the compressor and condenser for carrying high pressure gas refrigerant to said condenser, a line having an expansion valve therein connecting the condenser and evaporator for carrying high pressure liquid refrigerant between said condenser and expansion valve and low pressure refrigerant between said expansion valve and said evaporator, a line connecting said evaporator and compressor for returning low pressure gas refrigerant to said compressor, and a refrigerant injection unit connected between the line connecting the condenser and evaporator and the compression chamber of the compressor for increasing the pressure of the high pressure liquid and for injecting a charge of same into said compressor during the compression stroke, said refrigerant injection unit including a stepped casing having a stepped piston therein, a line connecting one end of said piston directly with said compressor and a line connecting the other end with the compressor when the compressor is engaged in the compression stroke.

8. A heat pump comprising a compressor having a compression chamber, an evaporator, a condenser, a refrigerant, a line connecting the compressor and condenser for carrying high pressure gas refrigerant to said condenser, a line having an expansion valve therein connecting the condenser and evaporator for carrying high pressure liquid refrigerant between said condenser and expansion valve and low pressure refrigerant between said expansion valve and said evaporator, a line connecting said evaporator and compressor for returning low pressure gas refrigerant to said compressor, and a refrigerant injection unit connected between the line connecting the condenser and evaporator and the compression chamber of the compressor for increasing the pressure of the high pressure liquid and for injecting a charge of same into said compressor during the compression stroke, said refrigerant charging unit including a stepped casing having a stepped piston therein, a line connecting the larger end of said piston directly with said compressor and a line connecting the smaller end of the piston with the compressor during the compression stroke.

9. A heat pump comprising a compressor having a compression chamber, an evaporator, a condenser, a refrigerant, a line connecting the compressor and condenser for carrying high pressure gas refrigerant to said condenser, a line having an expansion valve therein connecting the condenser and evaporator for carrying high pressure liquid refrigerant between said condenser and expansion valve and low pressure refrigerant between said expansion valve and said evaporator, a line connecting said evaporator and compressor for returning low pressure gas refrigerant to said compressor, and a refrigerant injection unit connected between the line connecting the condenser and evaporator and the compression chamber of the compressor for increasing the pressure of the high pressure liquid and for injecting a charge of same into said compressor during the compression stroke, said refrigerant injection unit including a stepped casing having a stepped piston therein, a line connecting the larger end of said piston directly with said compressor and a line connecting the smaller end of the piston with the compressor during the compression stroke, and means in said casing acting on said piston to return it to normal position after the injection stroke.

10. A heat pump comprising a compressor having a compression chamber, an evaporator, a condenser, a refrigerant, a line connecting the compressor and condenser for carrying high pressure gas refrigerant to said condenser, a line having an expansion valve therein connecting the condenser and evaporator for carrying high pressure liquid refrigerant to said evaporator, a line connecting said evaporator and compressor for returning low pressure gas refrigerant to said compressor, and a refrigerant injection unit including a casing having large and small contiguous stepped bores and a movable piston therein having large and small stepped portions, lines communicating both ends of the piston to the compressor, a check valve in the line communicating the small end of the piston with the compression chamber of the compressor permitting refrigerant flow only from the injection unit to the compressor, a line communicating the small end of the piston with the line carrying the high pressure liquid refrigerant, and a check valve in said last line permitting refrigerant flow only to the injection unit, whereby said piston is activated by the compressor during the compression stroke to inject a measured charge of refrigerant into said compressor.

11. A heat pump comprising a compressor having a compression chamber, an evaporator, a condenser, a refrigerant, a line connecting the compressor and condenser for carrying high pressure gas refrigerant to said condenser, a line having an expansion valve therein con-

necting the condenser and evaporator for carrying high pressure liquid refrigerant to said evaporator, a line connecting said evaporator and compressor for returning low pressure gas refrigerant to said compressor, and a refrigerant injection unit including a casing having large and small contiguous stepped bores and a movable piston therein having large and small stepped portions, lines communicating both ends of the piston to the compressor, a check valve in the line communicating the small end of the piston with the compression chamber of the compressor permitting refrigerant flow only from the injection unit to the compressor, a line communicating the small end of the piston with the line carrying the high pressure liquid refrigerant, and a check valve in said last line permitting refrigerant flow only to the injection unit, and means for limiting the movement of said piston to control the quantity of the measured charge, whereby said piston is activated by the compressor during the compression stroke to inject a measured charge of refrigerant into said compressor.
